(57) **CLAIM**

The ornamental design for a weight, as shown and described.

DESCRIPTION

FIG. 1 is a view in perspective of one side and a circumferential surface of the ornamental design of weight of this invention;

FIG. 2 is a view in perspective and of the reverse side of the weight shown in FIG. 1;

FIG. 3 is a view in front elevation;

FIG. 4 is a view in rear elevation; and,

FIG. 5 is a top plan view, the circumferential surface shown being uniform throughout the circumference of the weight.
